PHOTOELECTRIC CELL MOUNTING

Robert K. Dahlstrom and Daniel W. Ross, Silver Spring, Md., assignors to the United States of America as represented by the Secretary of the Navy

Application July 18, 1945, Serial No. 605,650

3 Claims. (Cl. 136—89)

This invention relates to photoelectric devices and has particular reference to a photovoltaic cell mounting of novel construction which is particularly adapted for use in photoelectric fuzes for explosive projectiles.

It has been proposed heretofore to detonate explosive projectiles automatically in the vicinity of the target, such as an airplane, by means of a fuze employing a control element in the form of a photoelectric cell which is influenced by a change in the amount of light reaching the projectile when the latter is in close proximity to the target. A fuze of this type is disclosed in a copending application of J. E. Henderson et al., Serial No. 568,020, filed December 13, 1944. In fuzes of this character, it is necessary to mount the photoelectric cell in such a manner that it will not be damaged by the shock incident to firing the projectile carrying the fuze. It will be evident that this shock is of considerable magnitude, particularly in the case of high velocity projectiles. Additionally, it is desirable to provide a mounting for the photoelectric cell which is of compact construction, since the space factor is of great importance in projectile fuzes. Also, in order that the fuze may be suitable for large scale production, it is desirable to provide a photoelectric cell mounting which may be quickly and easily assembled and is of relatively simple construction.

One object of the present invention, therefore, resides in the provision of a photoelectric cell mounting for projectile fuzes which is simple and compact in construction, may be readily assembled, and has a high degree of ruggedness so that the cell is capable of withstanding, without damage, the shock incident to firing the projectile.

Another object of the invention is to provide a photoelectric cell mounting comprising a base having a recess for receiving the cell, an electrical conductor in the base and connected to one side of the cell, a resilient conducting element engaging the other side of the cell, and a locking member of conducting material mounted on the base over the recess for holding the conducting element and the cell in position in the recess and for connection to a second conductor, which with the first conductor is designed to connect the cell into a suitable control circuit.

Still another object of the invention resides in the provision of a photovoltaic cell mounting of the character described in which the resilient conducting element is in the form of a ring, and the locking member has an opening alined with the ring opening for admitting light to the cell in the base.

A further object of the invention is to provide a photovoltaic cell mounting of the character described in which the resilient conducting element is made of conducting rubber, whereby the element serves the dual function of electrically connecting the cell into a circuit and cushioning the cell against shock.

These and other objects of the invention may be understood by reference to the accompanying drawing, in which

Fig. 1 is an exploded, perspective view of one form of

2

the new photovoltaic cell mounting, showing parts of the mounting in section, and

Fig. 2 is a longitudinal central sectional view of the assembled mounting shown in Fig. 1.

Referring to the drawing, the numeral 11 designates the base member of the photovoltaic cell mounting which is designed to be mounted in the nose portion of a photoelectric proximity fuze (not shown) so that the upper end of the base is exposed to daylight during flight of a projectile carrying the fuze. The base 11 is made of electrical insulating material, for example, "Bakelite" and is provided with an upstanding axial standard or boss 12 which, at its upper end, is cut away to form a circular cylindrical recess 13. A bore 14 extends axially through the base and the standard and communicates with the bottom of recess 13 at its central portion.

A contact plate 15 is seated on the bottom of recess 13, the plate being formed of foil, thin sheet metal, for example, cadmium-plated brass, or other electrical conducting material. An electrical conductor 16 extends through bore 14 and is electrically connected to the central portion of plate 15, as by means soldering 16a.

Mounted on the upper face of contact plate 15, within the recess 13, is a photovoltaic cell 17 of conventional design, the upper face of the cell being light-sensitive and having a contact rim 18. A resilient conducting ring 19, which may be made of conducting rubber, is fitted in the recess 13 above the cell 17 and is seated on the cell rim 18.

A locking ring 20, made of electrical conducting material, is fitted in the upper end of recess 13 and serves to retain the ring 19 and the cell 17 in tight engagement with each other and with the contact plate 15 within the recess. The locking ring 20 may be secured to the base 11 in any suitable manner, as by press-fitting the ring into recess 13. A central opening 21 in the locking ring 20 is alined with the opening in ring 19, so that light rays may pass through the opening 21 and the ring 19 and impinge upon the upper, light-sensitive surface of the cell 17.

The locking ring 20, as shown, has a peripheral flange overlying the upper end of the standard 12 and connected to an electrical conductor 22, as shown at 22a, the conductor being disposed in a longitudinal passage 23 in the base. It will be understood that the conductors 16 and 22 extend to the usual amplifier of the fuze (not shown) and serve to connect the cell in circuit with the amplifier.

The new fuze is of simple construction and may be readily assembled by inserting the resilient ring 19, the cell 17 and the conducting plate 15, with wire 16 attached, in the recess 13 and bore 14, and locking the parts in the recess by the locking plate 20, with the wire 22 attached. When the cell mounting is assembled, the parts are held securely in their proper positions by the locking ring 20 which, with the resilient ring 19 and the wire 22, serves as an electrical connection to one side of the cell. The ring 19 acts not only as part of the conducting path from one side of the cell but also as a cushion for preventing damage to the cell due to shock incident to handling or firing the projectile. The ring 19 is initially compressed by the locking ring 20 in assembling the mounting, with the result that good electrical connections are assured between the parts in the recess 13 at all times, due to the tendency of the ring 19 to press the parts together.

We claim:

1. An insulating body member having a cavity opening through a surface thereof, a contact element in said cavity, a conductor in electrical contact with said element and extending through the body member in a direction away from said surface, a photoelectric cell in said cavity,

said cell having one face in electrical contact with the contact element, a washer made of resiliently yieldable, non-metallic, electrically conducting material and in annular engagement with the other face of the cell, a conducting ring serving as a partial closure of the cavity and acting also to hold the contents of the said cavity firmly in place and under sufficient pressure to cause the washer to maintain good electrical contact between the cell and the conductors on opposite sides thereof, and a conductor electrically connected with said ring and extending through the body member in a direction away from the surface that has the cavity.

2. An insulating body member having a cavity opening through a surface thereof, a conducting element in said cavity, a conductor in electrical contact with said element and extending through the body member in a direction away from said surface, a photoelectric cell in said cavity, said cell having one side facing toward the conducting element, a yieldable annular spacer made of resilient, non-metallic, electrically conducting material and in engagement with one face of the cell, a conducting ring serving as a partial closure of the cavity and acting also to hold the contents of the said cavity firmly in place and under sufficient pressure to cause the spacer

4
5 to maintain good electrical contact between the cell and the conductors on opposite sides thereof, and a conductor electrically connected with said ring and extending through the body member in a direction away from the surface that has the cavity.

6 3. A photovoltaic cell assembly having a shock-resisting mounting, for use in a projectile, said assembly comprising a base of insulating material having a cavity therein, a contact member seated in said cavity, a photovoltaic cell having one flat face resting upon said contact member to provide electrical connection therewith, a ring of resilient conductive rubber resting on the opposite face of said photovoltaic cell and providing electrical contact therewith, and a metal ring engaging the base and compressing the conductive rubber ring, thereby forcing the contents of the cavity together.
